TOOTH BRUSH

George Leslie Herrick, Westfield, N. J., and Joseph P. Hardie, Hartsdale, and Arthur Cobb, Jr., Bronxville, N. Y., assignors, by mesne assignments, to Bristol-Myers Company, New York, N. Y., a corporation of Delaware

Application January 31, 1936, Serial No. 61,792

7 Claims. (Cl. 15—167)

This invention relates to improvements in toothbrushes and particularly to the handles for such brushes.

It contemplates the provision of a toothbrush with a handle so disposed with relation to the bristle carrying head as to serve as a guide to the user in naturally presenting the bristles to the surface to be brushed without distortion of the hand and wrist of the user.

10 Another object is to provide cooperative means whereby the manipulation of the brush is made easy and the hand-grip bettered by registering the position of the index finger and thumb of the hand operating the brush. A feature of the invention, in this connection, is the arrangement of the head and handle on a common longitudinal axis so that the handle may be readily manipulated by the fingers and thumb to cause the bristles of the head to produce a desirable massaging action. The attainment of these objects is particularly valuable in educating the novice in the use of the brush, in part due to the unconscious handling as a result of the structure as herein-after described in detail.

25 The accompanying drawing referred to herein and constituting a part hereof, illustrates a preferred embodiment of the invention.

Figure 1 is a plan view.

Fig. 2 is an end view.

30 Fig. 3 is a section on line 3—3 of Fig. 1.

Fig. 4 is a cross section of a modified form, and

Fig. 5 is illustrative of the brush in position for use.

35 The improved brush comprises a head 6 within which are suitably mounted a plurality of tufts of bristles 7. For the purposes of description, the greatest area of the head 6 will be hereinafter referred to as the horizontal plane of the brush and the direction of projection of the bristle tufts 7 as the vertical plane of the brush. The head 6 extends rearwardly to the points 8—8 where it tapers sharply to form a neck 9. Just 40 beyond the neck 9, as shown at 10, the handle portion of the brush is extended at an angle of approximately 45° to the horizontal plane of the brush, best illustrated in Figures 2, 3, and 4.

This angularity, just described, is formed about a common longitudinal axis through the handle and the brush head 6, as described hereafter. The handle portion of the brush is thus disposed at an angle of approximately 45° to the vertical plane of the brush, or to the line of vertical projection of the bristle tufts 7. It has been found that the recited angular relationships

are the most desirable, but departure may be made therefrom.

From the point of angular displacement 10 the handle gradually widens in cross section, as at 11—11, until the point 12 of greatest width is 5 reached. Here, in the preferred form, a pair of suitably shaped shallow cavities 13 are formed in the handle, such cavities 13 being substantially opposed, of such configuration, and so disposed as to receive the thumb of a user in one 10 cavity 13 and the finger of a user in the other cavity 13 when the brush is held in the hand for a brushing operation. Figure 5 illustrates this. The floor of each cavity 13 is formed with a plurality of ridges 14 defining intermediate 15 grooves 15 presenting a non-slipping surface for engagement by the user's finger and thumb.

In the modified form, shown in Figure 4, only one cavity 13 is utilized and the non-slip feature is omitted presenting a smooth surface 16 upon 20 the floor of cavity 13.

From the point 12 the handle, designated as a whole by the numeral 17, gradually tapers in its horizontal width to the end 18, adjacent to which is an opening 19 for convenience in suspending 25 the brush when not in use. The edges of the handle 17 are slightly beveled, as at 20, 21, forming an intermediate portion 22, all meeting lines being slightly rounded so that, while defining the portions 20, 21 and 22, the edges of the handle 30 are not sharp, but present a gradual curve to the hand of the user. This treatment of the handle edges starts at the point 9 and extends to the end 18 of the handle 17.

The handle and head are made of any suitable 35 material, preferably molded in one piece, the bristles being applied to the head in the usual manner. As seen in Figure 5, it will be apparent that, with a brush embodying the herein described features, the bristles will be properly presented 40 to the teeth, the operating hand assuming a natural and comfortable position without the cramping distortion of the wrist usually resulting from the use of toothbrushes of the ordinary construction.

45 We claim:

1. In a toothbrush an elongated head having a substantially flat face, a handle extending from one end of said head and having a pair of substantially flat, broad, and substantially parallel 50 sides, said head and handle having a common longitudinal axis, bristles protruding from said face of said head, the ends of said bristles providing a working face the general plane of which is substantially parallel with said flat face of the 55

head, the head and handle being so disposed with relation to each other that a plane passing through said axis parallel with the flat sides of the handle is at a pronounced angle to a plane through said axis parallel with said flat face of the head, the construction and arrangement being such that when the brush is held naturally between the thumb and fingers with the wrist of the user extended in its natural position the working face of said bristles will be presented directly toward the teeth.

2. In a toothbrush an elongated head having a substantially flat face, a handle extending from one end of said head and having a pair of substantially flat, broad, and substantially parallel sides, said head and handle having a common longitudinal axis, bristles protruding from said face of said head, the ends of said bristles providing a working face the general plane of which is substantially parallel with said flat face of the head, the head and handle being so disposed with relation to each other that a plane passing through said axis parallel with the flat sides of the handle is at an angle of about 45° to a plane through said axis parallel with said flat face of the head, the construction and arrangement being such that when the brush is held naturally between the thumb and fingers with the wrist of the user extended in its natural position the working face of said bristles will be presented directly toward the teeth.

3. In a toothbrush an elongated head having a substantially flat face, a handle extending from one end of said head and having a pair of substantially flat and substantially parallel sides, said head and handle having a common longitudinal axis, bristles protruding from said face of said head, the ends of said bristles providing a working face the general plane of which is substantially parallel with said flat face of the head, the head and handle being so disposed with relation to each other that a plane passing through said axis parallel with the flat sides of the handle is at an angle of about 45° to a plane through said axis parallel with said flat face of the head, the construction and arrangement being such that when the brush is held naturally between the thumb and fingers with the wrist of the user extended in its natural position the working face of said bristles will be presented directly toward the teeth, at least one of the flat sides of the handle having a depression intermediate the edges thereof for the reception of the end of one of the digits of the hand.

4. A toothbrush comprising a substantially flat, elongated head and a relatively flat handle, said head and handle being connected end to end and having a common longitudinal axis, said head having a plurality of bristle tufts projecting therefrom, the ends of the bristle tufts providing a working face, the handle being twisted about said axis with respect to the head at a pronounced angle to dispose the general plane of said handle at a pronounced acute angle to the general plane of said working face.

5. A toothbrush comprising a substantially flat, elongated head having bristles projecting from a face thereof in a common direction, a relatively flat, broad, handle extending from one end of said head and so constructed and arranged as to be received between the thumb and finger tips, said head and handle having a common longitudinal axis and being twisted with respect to each other about said axis, the general plane of said handle being disposed at a pronounced acute angle to the general plane of said head and to the direction in which said bristles project.

6. A toothbrush comprising a substantially flat, elongated head having bristles projecting from a face thereof in a common direction, a relatively flat handle extending from one end of said head, said head and handle having a common longitudinal axis and being twisted with respect to each other about said axis, the general plane of said handle being disposed at an angle of about 45° to the direction in which said bristles project.

7. A toothbrush comprising an elongated head having a longitudinally extending bristle receiving face, an elongated handle connected end to end with said head and having a common longitudinal axis therewith, bristles projecting from said face of the head and providing a working face at their free ends, the handle being relatively broad and flat and having faces adapted to be held between the thumb and fingers, the general plane of said handle being at a pronounced acute angle to said face of the head, the construction and arrangement being such that when the handle is so held and the wrist is extended naturally said working face of the bristles will be presented directly toward the teeth.
